DESIGN FOR A COMBINED SHAVING MUG AND SHAVING CREAM DISPENSER

August Lange, Chicago, Ill.

Application September 17, 1938, Serial No. 79,959

Term of patent 7 years

To all whom it may concern:

Be it known that I, August Lange, a citizen of the United States and a resident of Chicago, in the county of Cook and State of Illinois, have invented a new, original, and ornamental Design for a Combined Shaving Mug and Shaving Cream Dispenser, of which the following is a specification, reference being had to the accompanying drawing, forming a part thereof.

In the drawing:

Fig. 1 is a top plan view of a combined shaving mug and shaving cream dispenser, showing my new design; and

Fig. 2 is a side elevation thereof.

I claim:

The ornamental design for a combined shaving mug and shaving cream dispenser, substantially as shown.

AUGUST LANGE.
